BOGIE FOR RAILWAY ROLLING STOCK

Jakob Waldvogel and Gaston Borgeaud, Winterthur, Switzerland, assignors to Schweizerische Lokomotiv- und Maschinenfabrik, Winterthur, Switzerland

Application July 29, 1947, Serial No. 764,328
In Switzerland April 29, 1946

Section 1, Public Law 690, August 8, 1946
Patent expires April 29, 1966

4 Claims. (Cl. 105—190)

1

Our present invention relates to a railway-vehicle bogie, on which the car body is supported by means of laterally disposed longitudinal and oscillatably suspended plate springs, and in which the space inside the frame and in the bogie centre portion may be kept free from bogie props, struts and guide parts.

Our invention consists in securing two floating beams or bolsters which are oscillatably suspended laterally on the bogie frame, to the ends of the longitudinally disposed plate springs, and in arranging the spring bands or buckles to permit a same of swinging, relative to the car body, as a unit about a vertical axis disposed in the longitudinal median plane of the car body, and of guiding the said spring bands in a plane transversal to the said median plane.

An embodiment of the invention, in form of a triple-axle bogie, is shown in the drawing, in which:

Fig. 1 shows a longitudinal section on line I—I of Fig. 2,

Fig. 2 a plan view,

Fig. 3 is a cross-section on line III—III of Fig. 2, and

Fig. 4 a cross-section on line IV—IV of Fig. 2.

Fig. 5 is a view similar to Fig. 1 with parts omitted to show other parts.

The bogie frame 1 is resiliently supported on the boxes 2 of axles 3 through springs 34 guided on vertical pins 35, the said boxes for such purpose being provided with lateral arms 2a. The sills 4 of bogie frame 1 are interconnected by transoms 5 on either side of the intermediate axle 3. Sills 4 and transoms 5 are formed as box girders.

A bolster or floating beam 6 each is suspended, fore and aft of the bogie-frame center, from the bogie frame by means of swing links 7, i. e. laterally oscillatable. The bolsters 6 are provided with forked ends, and connected to the laterally disposed bearing springs by means of pins 10 threaded through the forks 8 and the curled-over spring eyes of the plate springs 9.

The car-body 13, depending on both sides, is supported on the spring bands or buckles 12. To permit frame 1 of oscillating, relative to body 13, on a horizontal cross-axis, a cradle 15 having a cylindrical convex head and fastly secured to the spring band 12, is interposed into the said supporting arrangement. Spring band 12 is held longitudinally immovable, relative to the bogie frame 1, by means of a tie 17 fastly secured to the latter, and by a longitudinal guide link 16 the ends of which are mounted in spherically shaped

2

bearings. Bogie and spring bands are permitted of swinging together about the king pin 23, relative to car body 13. To such end, the recessed bearing plate 18, mounted on the convex head of cradle 15, is provided with shouldered or stepped guide faces 19 of cylindrical form. The cylinder axis of the said faces 19 is vertical and passes, in the neutral or balanced position of bolsters 6, through king pin 23. The said guide faces 19 are engaged or guided by correspondingly adapted cylindrical guide faces of the shoe or slide plate 20 which is fixed to the car-body 13.

The bogie king-pin 23 is mounted in a U-shaped underslung longitudinal beam 24 which is depressed below the intermediate axle 3, and the ends of beam 24 are fastly secured to the two transoms 5 of bogie-frame 1. A transversely two-armed balancing lever 25 is pivoted on king-pin 23, and is engaged at its ends by the links 27 and 28, which act in opposite directions. The free ends of links 27, 28 are pivoted to the studs 29 of the two transoms 30 which are disposed fore and aft of the king pin 23, and fixed to the vehicle body. The ends 33 of transoms 30 are fastly secured to the posts 32 of car-body 13.

The curled-over ends or eyes of plate springs 9 shall bear in the forks 8 of the bolsters 6 on as wide a base as possible. To such end, two juxtaposed plate-spring packets advantageously are used (Figs. 2—4), which are fastly secured to spring band 12. The bearing members provided on the top face of spring band 12, therefore, also should have a correspondingly wide base, and the difference in elevation between the said members and the pins 10 of the plate-spring eyes shall be as small as possible. Springs 9 of maximum width also are desirable, since in such case the bolsters 6, which form an articulated quadrangle (appearing as rectangle in plan view), may be fixedly secured to the springs in the corners of such quadrangle, thus preventing a variation of the angular position of the springs relative to bolsters 6.

As may be seen from the drawing, such oscillatable spring support of the car-body on the bogie-frame permits of providing an intermediate or third axle-and-wheel set and, if necessary, of also mounting an electric motor above the said set, in that sufficient room in the bogie centre is held unobstructed for such purpose. The arrangement described also affords the possibility of providing a depressed king pin.

What we claim and desire to secure by Letters Patent is:

55 1. In a railway vehicle having a car body, a

triple-axle bogie the wheel sets of which have axle boxes, said bogie having a frame resiliently supported on the axle boxes, and the car body being resiliently supported on the bogie frame, a plurality of inverted plate springs disposed longitudinally on either side and outside of the central portion of each said bogie and symmetrical to the central axle thereof, means for supporting the car body transversely movably on the midpoint bands of said springs, a pair of transverse bolsters for each bogie pivoted longitudinally rockably to the end of said springs, king pin-and-link means for connecting each bogie to the car body, and means for suspending both ends of each said bolster in a transversely swingable sense from each said bogie, the said bolsters being disposed on either side of said central wheel set so as to form together with the said springs a closed pendulum-cradle in each bogie, which cradle encloses a free space on either side of said central wheel set and below each bogie.

2. In a railway vehicle set out in claim 1, spring bands of a width to accommodate at least two juxtaposed car-body supporting-springs, and circular-arc guideways in said spring bands for laterally guiding the car body, the center of said

guideways coinciding with the center of rotation of the respective bogie.

3. In a railway vehicle set out in claim 1, longitudinally disposed guide links to rockably guide the said pendulum-cradle transversely of the bogie, said links connecting the spring bands of the longitudinally disposed car-body supporting-springs to the respective bogie frame.

4. In a railway vehicle set out in claim 1, the said bolsters being depressed below the bogie sills for the purpose of lowering the car-body supporting-springs to permit the use of longitudinal car-body girders of high section modulus and to attain a smooth running of the vehicle.

JAKOB WALDOGEL.
